QUICK DETACHABLE ELECTRIC LAMP AND
SOCKET CONSTRUCTION

Carl August Johnson, Astoria, Long Island, N. Y.

Application June 12, 1940, Serial No. 340,127

5 Claims. (Cl. 176—32)

This invention relates to quick detachable electric lamp and socket construction.

An object of this invention is to provide a quick detachable electric lamp and socket construction, in which the socket is provided with a split cylindrical ring formed with a plurality of longitudinally spaced inwardly projecting projections, and in which the lamp has a base formed with a pair of annular grooves, the base being insertable into the ring and the projections being adapted to snap into the annular grooves to detachably attach the lamp to the socket, the socket being provided with a central contact to engage the central contact of the lamp when the projections engage within the grooves, and the lamp being adapted to be pulled out a distance sufficient to permit disengagement of the central contact of the socket with respect to the central contact of the base, and in such position, one of the projections being received within one of the annular grooves so that the lamp is attached to the socket, without being electrically connected to the terminals of the socket.

A further object of this invention is to provide an improved socket and lamp construction of the character described, in which the lamp has a base which may be longitudinally inserted into the socket in any angular position of the lamp relative to the socket, so that the lamp does not have to be rotated about its axis to any particular position before insertion into the socket.

Still a further object of this invention is to provide a highly improved quick detachable lamp and socket construction of the character described, which shall be relatively inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a side elevational view of a socket and lamp construction embodying the invention, with parts in cross-section and showing the lamp in dot dash lines, in a position where the terminals of the lamp are not in electrical engagement with the terminals of the socket;

Fig. 2 is a bottom plan view of the socket;

Fig. 3 is a side elevational view of the inner split ring inverted; and

Fig. 4 is a side elevational view of the lamp.

Referring now in detail to the drawing, 10 designates a quick detachable electric lamp and socket construction embodying the invention, and comprising a socket 11 and a lamp 12 quickly detachable thereto in the manner hereinafter explained.

The socket 11 has a head 14 and a downwardly extending cylindrical wall 15. The head 14 may be provided with a usual switch, not shown, and within said head is a block 16 of insulating material forming the top of the socket opening, and mounted thereon, is a central spring contact 17 of usual construction.

Said member 16 is furthermore formed with diametrically opposed screw threaded openings receiving screws 18. The screws 18 may be connected to one terminal within the socket, whereas, the central contact 17 may be connected to the other terminal of the socket.

Within the cylindrical wall 15, is a cylindrical sleeve 20 of insulating material. Within said cylindrical sleeve 20 is a split cylindrical ring or sleeve 22 of conducting material. The sleeve 22 is formed with a longitudinal split 23, as shown in the drawing.

Extending from diametrically opposite sides of the ring or sleeve 22 are upwardly extending parallel arms 24 formed with inwardly apertured ears 25 contacting the under-surface of member 16. The ears 25 are preferably equidistant from the split 23. The screws 18 pass through the apertured ears 25 and serve to attach the split ring sleeve or ring 22 to the block 16.

Said sleeve 22 is formed on opposite sides of the split 23 with a pair of longitudinally spaced, inwardly extending projections 26 and 27. It will be noted that the projections 26 and 27 on one side of the split are aligned with the projections on the opposite sides of the split. The sleeve 22 being attached to the screws 18, is electrically connected to one terminal of the socket.

The lamp 12 has a base 30 comprising a cylindrical wall 31 of conducting material formed with a pair of longitudinally spaced annular grooves 34 and 35. The space between the grooves 34 and 35 is equal to the projections 26 and 27. The base 30 is furthermore formed with a central contact 36.

The lamp may be attached to the socket by pushing the base upwardly into the socket until the projections 26 and 27 snap into the grooves 34 and 35, respectively. When the projections

26 and 27 are in the grooves, the central contact 17 of the socket will engage the central contact 36 of the lamp, so that the lamp will be in circuit with the terminals 17 and 18.

The split ring 22 is resilient to permit the base to be pushed upwardly and to furthermore permit the projections 26 and 27 to snap into the grooves.

It will be noted that the lamp may be rotated within the socket and may be attached thereto in any angular position of the lamp about its axis.

The lamp may be removed from the socket by merely pulling the lamp downwardly.

Furthermore, the lamp may be electrically disconnected from the socket without removing the lamp from the socket. Such operation may be accomplished by pulling the lamp downwardly sufficiently to permit the projection 27 to snap into the groove 34. In such position, the central contacts 17 and 36 will be disengaged to break the electrical connections for the lamp filament.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. In combination with a socket having a central contact connected to one terminal in the socket, and a metal sleeve within the socket connected to the other terminal of the socket, said metal sleeve being formed with a pair of longitudinally, spaced projections, a lamp having a base formed with an outer cylindrical sleeve of conducting material, and a central contact, the sleeve of the base being formed with a pair of annular grooves spaced apart a distance equal to the distance between the projections on the sleeve within the socket, whereby said base may be inserted into the sleeve of the socket to permit the projections to snap into said annular grooves.

2. In combination with a socket having a central contact connected to one terminal in the socket, and a metal sleeve within the socket connected to the other terminal of the socket, said metal sleeve being formed with a pair of longitudinally spaced projections; a lamp having a base formed with an outer cylindrical wall of conducting material, and a central contact, the cylindrical wall of the base being formed with a pair of annular grooves spaced apart a distance equal

to the distance between the projections on the sleeve within the socket, whereby said base may be inserted into the sleeve of the socket to permit the projections to snap into said annular grooves, said sleeve being split longitudinally.

3. In combination, a socket, a split cylindrical sleeve within said socket having diametrically disposed ears equiangularly spaced from the split in the sleeve, means for attaching said ears to the socket, said sleeve being formed on opposite sides of the split with a pair of longitudinally spaced, inwardly extending projections, and a lamp having a base formed with a fixed sleeve having a pair of annular grooves, said base being adapted to be pushed into the socket, and said projections being adapted to snap into said grooves.

4. In combination, a socket, a split cylindrical sleeve within said socket having diametrically disposed ears equiangularly spaced from the split in the sleeve, means for attaching said ears to the socket, said sleeve being formed on each of the opposite sides of the split with a plurality of longitudinally spaced, inwardly extending projections, and a lamp having a base formed with a fixed sleeve having a plurality of annular grooves, said base being adapted to be pushed into the socket, and said projections being adapted to snap into said grooves, said grooves and projections being equally spaced apart and spaced equal distances from the central contacts of said base and socket respectively, so that when the base is fully inserted into the socket, said central contacts will touch and when the lamp is pulled down a distance sufficient for the lower projection to snap into the upper groove, the central contact of the socket will be disengaged from the central contact of the base.

5. In combination with a socket having a central contact connected to one terminal of the socket and a lamp having a base formed with a plurality of spaced, annular, external grooves, and a central contact adapted to engage the central contact of the socket, a longitudinally split sleeve within the socket connected to the other terminal of the socket and having means on opposite sides of the split for engagement within one or more of the grooves to retain the central contact of the base in engagement with the central contact of the socket while permitting rotation of the lamp relative to the socket, said groove engaging means being so arranged as to permit the lamp to be partially pulled longitudinally away from the socket and engageable with one of the grooves to retain the lamp base within the socket with the central contact of the base out of engagement with respect to the central contact of the socket.

CARL AUGUST JOHNSON.
